UNITED STATES PATENT OFFICE.

JOHN EWIG, OF WASHINGTON, DISTRICT OF COLUMBIA, ASSIGNOR TO
OTTOMAR MENGER, OF PHILADELPHIA, PENNSYLVANIA.

WAISTBAND-FASTENER.

SPECIFICATION forming part of Letters Patent No. 408,300, dated August 6, 1889.

Application filed November 9, 1887. Renewed July 1, 1889. Serial No. 316,166. (No model.)

To all whom it may concern:

Be it known that I, JOHN EWIG, a citizen of Washington, residing at Washington, in the District of Columbia, have invented certain new and useful Improvements in Waistband-Fasteners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to a new and improved fastening for the meeting parts of garments, and is more especially intended for the "fly" of pantaloons, and is in the nature of an improvement on the device for which I applied for Letters Patent on the 8th day of June, 1887, which application was allowed the 27th day of June, 1887, and has for its object to provide a fastening that may be quickly and easily applied to the garment, and when so applied the meeting parts of the garment may be readily and securely fastened one to the other.

To this end my invention consists in the fastening hereinafter fully described, and more particularly pointed out in the claims, due reference being had to the accompanying drawings, wherein—

Figure 1 is a perspective view showing the fastening device attached to a garment; Fig. 2, a perspective view of the hook; Fig. 3, a perspective view of the hook from the rear; Figs. 4 and 5, modifications of the catch; Fig. 4^a, a view of the blank from which the catch is made; Fig. 6, a longitudinal section of the catch; Fig. 7, a side elevation of the catch, and Fig. 8 a modification thereof.

Referring to the drawings, the letter A indicates one member of my fastening, consisting of a piece of sheet metal rounded at one end and having a semicircular slot in said end. Said slotted and rounded end is bent over and back upon the body of the member A to form a hook B, and is bent so as to leave shoulders e projecting beyond the edge of the body A, for the purpose hereinafter described. The base or body portion of the member A

is provided with perforations a for the passage of the threads employed for securing the member to the garment.

C indicates the other member of my fastening, consisting in one instance, as shown in Fig. 1 of the drawings, of a plate perforated at each end for the passage of the threads employed in securing the same to the garment, and in the other instance it consists of a staple, as shown in Figs. 4, 5, 6, 7, and 8 of the drawings, constructed as follows: I take two blanks C, of the form shown in Fig. 4^a, each consisting of a body portion c, and provided at each end with a prong a', and secure the two blanks together by soldering or riveting the body portions together, or otherwise suitably fastening them one to the other. The prongs a' are then bent at right angles to the body portion c.

In Fig. 7 I have shown a simple method of securing the blanks together. In this method the blanks are laid one upon the other, and the ends of the body portion c are bent back upon themselves, as shown at c', and the prongs a' then bent at right angles to the body portion c.

In Fig. 8 is shown a modified form of construction of the staple. As shown in this figure, c indicates the body portion, and a' the prongs. Each pair of prongs consists of a piece of sheet metal bent at its middle to form the prongs and then bent at right angles to the prongs, as at a³, Fig. 8. The ends of the body portion c are then bent over the bent portions of the prongs with considerable pressure, firmly uniting the prongs with the body portion c.

When used on some kinds of material, I find that the edges of the prongs a' are liable to cut the cloth, and to prevent this I provide the prongs a' with ears a², (see Figs. 4 and 5,) which are bent back upon the prongs, forming on said prongs at the point where they penetrate the cloth rounded edges, thus obviating all liability of the cloth being cut by the sharp edges of the prongs.

The fastening is applied to a garment as follows: The body portion of the member A is placed between the two layers of cloth forming the edge of the garment in such a man-

ner that the hook B will be upon the inside of the garment. Stitches are then passed through the perforations *a* and through the cloth. I have found in practice that where 5 the hook B is at all wide the edges of the cloth are not sufficiently supported by the threads, and to remedy this defect I cut away the center of the hook to form a slot *b*, as shown in Figs. 1, 2, and 3 of the drawings, and 10 the hook portion B is so bent over upon the body portion A as to leave shoulders *e e* projecting beyond the said body portion A, which allows the two layers of cloth on each side of the member A to meet slightly beyond the edge 15 of the member A, and permits the cloth at its edges to be stitched through said slot, thus not only permitting the cloth to be stitched substantially along its entire edge, but also assisting in firmly securing the member A in 20 place. To the edge of the garment opposite the hook B is secured the catch C. As shown in Fig. 1, the catch consists simply of a plate perforated at each end and secured to the cloth by threads passing through the perforations. 25

As shown in Figs. 5, 6, 7, and 8, and as before described, the catch C consists of a staple having two prongs at each end, and is secured in place by passing the prongs through the 30 cloth and then bending or clinching them down on the reverse side of the cloth. In fastening the meeting edges of the garment

together said edges are brought together and the hook B passed under the catch C in the usual manner.

35

Having thus described my invention, what I claim is—

1. In a garment-fastening, the combination, with a catch C, of the plate A, having the rounded hook B, provided with a semicircular slot and the shoulders *e e*, said plate A being perforated at *a a*, substantially as shown and described, and for the purpose specified. 40

2. In a garment-fastening, the combination, with the plate A, provided with the hook B, of the catch C, consisting of two plates having prongs at each end, said plates being secured one to the other and the prongs bent at right angles thereto, substantially in the manner shown and described, and for the purpose 45 specified.

3. In a garment-fastening, the combination, with the plate A, provided with the hook B, of the catch C, consisting of the body *c*, having prongs *a'* at each end, said prongs being provided with ears *a²*, substantially as shown and described. 50

In testimony whereof I affix my signature in presence of two witnesses.

JOHN EWIG.
